UNITED STATES PATENT OFFICE.

CHARLES KARPP, OF NEW YORK, N. Y.

TYPE AND TYPE-BAR.

1,359,664

Specification of Letters Patent. Patented Nov. 23, 1920.

Application filed October 3, 1919. Serial No. 323,115.

To all whom it may concern:

Be it known that I, CHARLES KARPP, a citizen of the United States, and a resident of the city of New York, borough of the Bronx, 5 in the county of Bronx and State of New York, have invented a new and Improved Type and Type-Bar, of which the following is a full, clear, and exact description.

This invention relates to improvements in 10 type and type bars, and more particularly for type and type bars such as used on typewriters, an object of the invention being to provide an improved construction of type and type bar and improved means for se- 15 curing the type to the type bar so as to insure a perfect alinement to rigidly and per- manently connect the type to the bar and to obviate the use of solder as commonly em- ployed for the purpose.

20 A further object is to provide improve- ments of the character stated, which sim- plify the assemblage of parts and in which the operation can be readily carried out by anyone of average intelligence, not requiring 25 skilled labor for the purpose.

To provide a construction of type bar and type with the improved means for securing them together which will absolutely prevent displacement of the parts and which will in- 30 sure a perfect alinement is the primary ob- ject of my invention and in the accomplish- ment of this object certain novel features of construction and combinations and arrange- ments of parts are resorted to, as will be more 35 fully hereinafter described and pointed out in the claims.

In the accompanying drawings—

40 Figure 1 is a plan view illustrating the manner of assembling the type and type bars;

Fig. 2 is an enlarged view in section on the line 2—2 of Fig. 1;

Fig. 3 is a view in transverse section on the line 3—3 of Fig. 2;

45 Figs. 4 and 5 are enlarged fragmentary views in elevation of the opposite faces of the end of the type bar;

Figs. 6 and 7 are similar views showing the type bar with the type attached;

50 Fig. 8 is a view in section on the line 8—8 of Fig. 6; and

Fig. 9 is a view in section on the line 9—9 of Fig. 7.

1 represents a slotted segment, such as is

commonly employed on the typewriter for 55 pivotally supporting the type bars 2, and it is, of course, to be understood that the type bars are so shaped that a particular bar is de- signed to fit a particular slot as is customary in the art.

60

3 represents a notched guide plate which is secured to the segment 1 and 4 is an alinement plate which I secure to the segment and which is made with a groove 5 to receive the type 6 therein and support the same in 65 proper position for engagement with the type bar 2.

It is, of course, to be understood that the operation of assembling the type on the type bar is done entirely separate from the 70 typewriter and the bars with the type thereon are to be furnished and assembled during the assemblage of the machine. I merely utilize the segment 1 similar to that on the typewriter in order to properly assemble the 75 type and bars together.

The type 6 has the usual pair of type faces 7 at its edge and is of general bifurcated form in transverse section, the two members 8 and 9 snugly fitting against the sides of the type 80 bar 2. The type bar 2 in one face has a groove 10, but its other face is normally smooth and without irregularity in surface. These two sides of the type bar are best illus- 85 trated in Figs. 4 and 5. The two members 8 and 9 before assemblage of the parts are also smooth and without projections or in- dentations of any character.

When the type 6 is in the groove 5, as shown in Fig. 1, the type bar 2 is moved so 90 that its free end enters the bifurcated type. While in this position a suitable tool, not shown, having a pair of jaws is brought into operation. One jaw of said tool acts to press or force the intermediate portion of the 95 member 8 tightly into the groove 10 of the type bar, as clearly shown in Fig. 6, while the other member serves to punch transverse indentations 11 into the member 9 of the type in a plane at right angles to the plane 100 of the type. These indentations, as illus- trated, are preferably in alinement with the groove 10 and they constitute in effect lock- 105 ing spurs or lugs which bite into the metal of the type bar 2 as shown in Fig. 9. I preferably provide a plurality of these in- dentations which manifestly coöperate or act with the inwardly pressed metal of the

intermediate portion of the member 8 in the groove 10 whereby the type is permanently and securely locked to the type bar and independent movement thereof in any direction and however slight is thus impossible.

The connection is such a secure one that the device will stand all of the pounding to which type of this character necessarily is subjected and will maintain a perfect 10 alinement for a maximum length of time. In fact the alinement is assured by the manner of assembling the type and the bar, as shown in Fig. 1, and hence it is not necessary for an operator to adjust the type to secure 15 a perfect alinement during the assemblage of the typewriter as the type and bars are perfectly formed before the assemblage of the typewriter is attempted and hence the operation of assembling the typewriter is 20 facilitated and a superior machine is the result.

Various slight changes may be made in the general form and arrangement of parts described without departing from the invention, and hence I do not limit myself to the 25 precise details set forth but consider myself at liberty to make such changes and altera-

tions as fairly fall within the spirit and scope of the appended claims.

I claim:

1. The combination with a type bar having a groove in one face, of type having a bifurcated body portion receiving the bar, one member of said bifurcated portion being pressed into the groove of the bar and transverse indentations in the other member of the body portion punched into the other face of the bar and coöperating with the pressed in portion of said first member to lock the type to the bar and against independent movement in any direction. 30 35

2. The combination with a type bar having a groove in one face, of type having a bifurcated body portion receiving the bar, one member of said bifurcated portion being 40 pressed into the groove of the bar and the other member of said bifurcated portion having indentations punched therein and into the bar in substantial alinement with said groove and coöperating with the pressed 45 in portion of said first member to lock the type to the bar and against independent movement in any direction. 50

CHARLES KARPP.
